ICE BREAKER

Filed Dec. 20, 1922

2 Sheets-Sheet 2

UNITED STATES PATENT OFFICE.

JOHN ALBERT ELLIS, OF IBERVILLE, QUEBEC, CANADA.

ICE BREAKER.

Application filed December 20, 1922. Serial No. 608,130.

To all whom it may concern:

Be it known that I, JOHN ALBERT ELLIS, a subject of the King of Great Britain, and resident of the village of Iberville, in the Province of Quebec and Dominion of Canada, have invented certain new and useful Improvements in Ice Breakers, of which the following is a specification.

This invention relates to improvements in ice breakers and more particularly to that type of ice breaker for use in clearing navigable water-ways of ice.

The objects of the invention are to provide an efficient and economical ice breaker, in which the several parts will satisfactorily perform the various functions required of them when in operation.

With these and other objects in view, the invention consists essentially in the novel construction and arrangement of parts as described in the present specification and illustrated by the accompanying drawings forming part of the same.

Referring to the drawings, in which like characters of reference indicate corresponding parts in each figure,

Figure 1 is a side elevation of the ice breaker with parts cut away showing the ballast tanks.

Figure 2 is a top plan view.

Figure 3 is a perspective detail of the caterpillar mechanism, showing the ice breaking teeth.

Figure 4 is a cross section.

In the drawings, A designates a power propelled boat or the like, here shown as steam driven and provided with the usual propeller B, while mounted on the bow of the boat are the ice breakers C, D representing the engine and mechanism for driving the ice breakers.

The ice breaker C comprises in combination with the bow 10 of the boat and upper and lower supporting brackets 11 and 11^a, a plurality of spaced guide-ways suitably mounted on said brackets and designed to extend outwardly in triangular formation, as shown in Figure 1. These guide-ways or frames are formed of channel iron and are provided with a plurality of rollers 13 on which are designed to travel the endless caterpillar chain members 14 formed with the ice gripping and breaking teeth 15. The chains 14 are adapted link by link to engage with suitably formed (here shown as hexagonal) pulleys 17, 18 and 19 mounted in each

corner of the triangles formed by the guide-ways 12. These pulleys 17, 18 and 19 are mounted respectively on shafts 20, 21 and 22, shaft 20 extending transversely through the apices of the guide-ways 12 and shafts 21 and 22 extending transversely one above the other and mounted on the brackets 11 and 11^a.

22 constitutes the main driving means for the caterpillar chains 14 and is connected through gear wheels 23 on the shaft 22 with gear wheels 24 on the auxiliary driving shaft 26. 27 is the main driving shaft of the engine and is chain connected to the auxiliary shaft 26 by two sprocket wheels 28 on the former and sprocket wheels 29 on the latter.

30 are fly wheels on the main shaft 27 and 31 is a gear thereon designed to mesh with the gear 32 of the engine mechanism, whereby, by means of a lever member 33, the said driving mechanism for the ice breakers is controlled. 34 are ballast tanks in the front and rear of the boat designed in combination with the ice breaking mechanism to reinforce same by means of added weight when the boat is moving. 35 is an adjustable box for the shaft 20 operated by an adjusting screw 36, whereby the shaft 20 is moved backwards and forwards to slacken or tighten, as may be required, the caterpillar chains 14.

From the foregoing it will be seen that I have invented an ice breaker designed on the caterpillar pattern with solid iron gripping and breaking teeth mounted on endless chains and on the bow of the boat and in such a way that the weight of the teeth, when in operation, will be reinforced by the forward moving power and weight of the boat, which may also be reinforced by means of ballast tanks, thus giving a tremendous power to the ice breakers, the idea being that as the endless chains are operated they will first grip the ice and draw the full weight of the boat as they revolve against it, thereby subjecting the ice to tremendous pressure from above and at the side. In other words, it is quite evident from visualizing the operation of my invention that it will be almost impossible for any ice to withstand it.

As many changes could be made in the above construction and many apparently widely different embodiments of my invention within the scope of the claims, con-

structed without departing from the spirit or scope thereof, it is intended that all matter contained in the accompanying specification and drawings shall be interpreted as 5 illustrative and not in a limiting sense.

What I claim as my invention is:

1. An ice breaker comprising in combination with the bow of a boat, supporting members on the boat, a plurality of spaced 10 guide-ways mounted on the supports and designed to extend outwardly in triangular formation, rollers in said guide-ways and endless chains provided with ice gripping and breaking teeth mounted on said rollers, 15 operating means for the chains comprising transversely extending shafts through said guide-ways having pulleys thereon designed to engage with the links of said chains, means connecting said shafts with suitable 20 driving means on the boat whereby on the driving means being operated the teeth carrying chains are set in motion to engage with and break the ice in combination with the forward movement of the boat, ballast- 25 ing tanks for the boat and adjustable mount-

ing means for one of said chain carrying shafts.

2. An ice breaker comprising in combination, supporting members, a plurality of spaced triangular guideways on the supports, rollers in said guideways, endless chains provided with ice gripping and breaking means for said rollers, operating means for the chains comprising transversely extending shafts, having means 30 thereon designed to engage with said chains, means connecting said shafts with suitable driving means whereby the teeth are set in motion to engage with and break the ice in combination with the forward movement 35 of the ice breaker, ballasting tanks for the ice breaker, and adjustable mounting means for one of said chain carrying shafts.

In witness whereof I have hereunto set my hand in the presence of two witnesses.

JOHN ALBERT ELLIS.

Witnesses:

JOS. AREL,
ALENE BOUSQUIT.
